[57] CLAIM

The ornamental design for a compartmentalized trash container, as shown and described.

DESCRIPTION

FIG. 1 is a top plan view of a compartmentalized trash container showing our new design;

FIG. 2 is a front elevational view thereof;

FIG. 3 is a sectional view thereof taken along the line 3—3 of FIG. 2;

FIG. 4 is a front perspective view of one of the trash containers; and,

FIG. 5 is a front perspective view thereof, the bottom container being opened and one of the trash container being removed from the rack for clarity of illustration.
